UNITED STATES PATENT OFFICE.

FRED H. MAYER, OF SALEM, OREGON.

ELECTRIC SWITCH.

Application filed January 3, 1925. Serial No. 337.

My invention relates to electric switches or devices for the making and breaking of an electric circuit through separable contact terminals, and consists in providing means for sealing such contact terminals in a de-oxygenized atmosphere, that is to say in a vacuum or in a properly confined volume of gas that is substantially free of oxygen.

Contact terminals which, in air, make and break an electric circuit, generate, by the arc produced in the make and break operation, nitric acid from the moisture of the air and its constituent elements, to wit, hydrogen, nitrogen, and oxygen. Nitric acid is, as is well known, a powerful oxidizer of all metals except gold and platinum, and its presence, considering the prohibitive cost of said metals, makes the commercial production of ordinary electric thermostatic switches, for example, practically impossible. This is due on the one hand to the prohibitive cost of acid resisting metals, and on the other to the short life in service of other metals.

By my invention it is made entirely practicable to use ordinary make and break copper contacts in electric switches for indefinitely long periods of time without necessity for renewal of the contacts or for attention to them of any sort. This application is a continuation in part of my copending application, Serial No. 595,288, filed October 18, 1922, which shows a switch of the character herein claimed embodied in an electric iron, and arranged so that the heat radiated by the resistance elements may be conducted through or penetrate the casing of the switch, and thereby affect the thermostatic element.

What constitutes my invention will be hereinafter specified in detail and succinctly defined in the appended claims.

In the accompanying drawing:

Figure I is a longitudinal section partly in side elevation of one form of embodiment of my invention.

Figure II is a view similar to Figure I, and of the same subject-matter, but taken at right angles to the view in Figure I.

Figure III is a view corresponding, in effect, to Figure II, but showing a modified form of embodiment of my invention.

Referring first to the numerals on Figures I and II of the drawing, 1 and 2 indicate, respectively, the two leads of an electric circuit which communicate with each other

through a source of electric energy, not illustrated. They are assembled by air tight joints with an insulating head 3, upon opposite sides of which they are respectively 60 united to conductive arms 4 and 5, which are provided, respectively, with contact terminals 7 and 8. Said terminals normally make contact in consequence of the cooperative resiliency of the arms 4 and 5. 65

One or both of the said arms is a thermostat whose action is controlled by a variable degree of the temperature to which they are exposed. At a predetermined critical degree of temperature, therefore, one or both 70 of the arms automatically bends so as to break the contact which normally exists between the terminals 7 and 8, thereby breaking circuit through the leads 1 and 2. 75

My invention consists in providing, in respect to such a combination in any variation of form which may be imparted to it, means for protecting the terminals 7 and 8 from the effects upon them of oxidation, to which they are exposed when surrounded by air. 80 To that end I provide an air-tight case 9 of heat penetratable or conducting material of any suitable character into which the arms 4 and 5 are introduced, and to which the head 3 is hermetically sealed. 85

The interior of the case 9 is provided with a deoxygenized atmosphere which the case confines to the exclusion of air. By the term "deoxygenized" I designate any gaseous atmosphere or a vacuum (so far as it 90 is attainable) which is either substantially or entirely free of oxygen. The atmosphere within the case 9 may be deoxygenized either by exhausting the oxygen of the air within it, or by entirely displacing the air with a 95 gas that is free of oxygen. Any known or preferred method for removing, in effect, the oxygen may be employed at will.

The terminals 7 and 8 may be made to 100 operate within an atmosphere such as has been specified so as to make or break circuit through their agency. The absence of oxygen in said atmosphere, by preventing the formation of nitric acid upon the terminals, prolongs, as has been already 105 specified, the life of them indefinitely, and makes it practicable to make them of a cheap metal, such, for example, as copper.

In Figure III, I show a modification of 110 the form of embodiment of my invention in which one of the elements shown in the preceding figures is eliminated, though in ef-

fect retained. In that figure, the leads 1 and 2 are connected, respectively, with the conductive head 10 of a thermostatic longitudinally curved or bent metal case 11, and 5 with a cooperative, preferably curved arm 12 carried by the head 10 within said case. The case 11 is flexible and is thermostatic in so far as it tends to straighten under heat in consequence of the expansion of the 10 gas confined within it. The heat necessary to effect that result may be developed from a source outside the case which, for this purpose, is of heat conducting or penetratable material as disclosed in my copending 15 application above referred to, or in any other suitable manner. The arm 12 is joined to the lead 2 through the head 10 from which said members are insulated as 20 by the aid of an insulating stuffing box 14.

20 The free end of arm 12 within the case 11 is provided with a contact terminal 15, which makes normal contact, substantially as illustrated, with a contact terminal 16 on the inside concave bend of the case. 25 Means of adjustment of the relationship of the arm 12 to the case 11 so as to effect such degree of nicety of contact between the terminals 15 and 16 as may be desirable, is represented by a screw 18 threaded in a block 30 19 provided on the outside of the case 11, and through an insulating block 20 within said case, interposed between the case and the arm 12.

35 In the modified form of embodiment of my invention last referred to as shown in Figure III, a sufficient tendency to straighten the bend of the case 11, induced by heat as above indicated, for example, will have the effect of breaking contact between 40 the terminals 15 and 16.

The case 11, like the case 9, and with like effect, confines within it a deoxygenized atmosphere.

45 Furthermore, by actuation of the screw 18, variation of pressure may be communicated through flexure of the case 11 to the arm 12 with the effect of adjusting the contact terminals, for example 15 and 16, towards each other. Such adjustment may 50 be employed not only if the arm 12 or the case 11 is, in effect, a thermostat, but it also instances means for positively actuating the terminals to make and break contact between them in the absence of any provision 55 for their automatic or thermostatic control.

The operation of my invention in any of its various forms of embodiment may be briefly described as follows.

Breaking of contact between any two contact terminals such, for example, as the terminals 60 7 and 8 or the terminals 15 and 16, is effected through a thermostat by elevation, to any predetermined critical degree, 65 of the temperature to which the instrument is exposed. Such raising of the temperature would, of course, result from heat generated by the electric circuit made by contact between the terminals included in it, and communicated, in any way as by induction or radiation, to thermostatically 70 responsive element of the instrument, to wit (in either of the two instances specified), to one or both of the arms 4 and 5 or to the atmosphere within the curved case 11.

75 Through adequate movement of the responsive element, induced either by variation of temperature or by manual actuation, contact between the terminals will be either made or broken, as the case may be. 80 At some point in the making and in the breaking of contact an electric arc will be formed between the terminals. If the terminals are at such time exposed to air, the 85 arc will generate nitric acid upon terminals of base metal, with injurious effect upon them, as already specified; but by aid of my invention, through exclusion of oxygen from the terminals, the generation of nitric acid will be eliminated. Consequently the 90 injurious effects upon the terminals will not follow, and the life of the terminals will be greatly and indefinitely prolonged.

What I claim is:

1. An electric switch comprising the combination with separable electric contact terminals, of a flexible, longitudinally bent conductive case en sealing said terminals therein, one of said terminals being operatively fixed to said case, and the case being adapted to straighten by expansion under heat of the atmosphere confined within it. 95

100 2. An electric switch comprising the combination with separable electric contact terminals of a flexible longitudinally bent conductive case en sealing said terminals within a deoxygenized atmosphere, one of said terminals being operatively fixed to said case and the other being flexibly mounted for adjustment relative thereto, said case being 105 adapted to straighten by expansion under heat of the atmosphere confined within it. 110

115 In testimony whereof, I have hereunto set my hand.

FRED H. MAYER.
